UNITED STATES PATENT OFFICE.

HARRY P. FAIRCHILD, OF NEW YORK, N. Y., ASSIGNOR TO FERMENE G. FAIRCHILD,
OF NEW YORK, N. Y.

EXTENSION FOUNTAIN-PEN.

1,185,388.

Specification of Letters Patent. Patented May 30, 1916.

Application filed October 16, 1915. Serial No. 56,171.

To all whom it may concern:

Be it known that I, HARRY P. FAIRCHILD, a citizen of the United States, residing at 412 West End avenue, New York, county 5 of New York, and State of New York, have invented certain new and useful Improvements in Extension Fountain-Pens, fully described and represented in the following specification and the accompanying drawings, forming a part of the same.

This invention relates to a new article of manufacture, consisting of a fountain pen having a body formed of the usual hard rubber or other hardened composition and 15 short enough to be conveniently carried in the pocket, and provided with telescopic metal coverings of special construction which can be extended for use sufficiently to make the same convenient and practical 20 for writing.

The invention will be understood by reference to the annexed drawing, in which—

Figure 1 shows the pen closed and adapted 25 to be carried in the pocket or carried as a charm, for which purpose a ring is provided upon the cap; Fig. 2 shows the pen extended and the cap removed and applied to the end of the extension-tube; Fig. 3 shows the body of the pen with the extension-tube in section and drawn out to the 30 farthest limit; Fig. 4 shows the shell separate from the body; Fig. 5 is a side view of the lining for the extension-tube; Fig. 6 is an elevation of the plug for the outer 35 end of the extension-tube; and Fig. 7 is a longitudinal section of the pen-cap. Fig. 8 is a section on line 8—8 in Fig. 3.

In the drawing, *a* designates the composition body of the pen having nozzle *b* to 40 carry the pen *c*, and shown provided with a short section of screw-thread *d* to retain the cap thereon. The shell *e* is pressed tightly upon the body as shown in Fig. 8, and provided with the lateral stud *f* at its 45 outer end.

The usual composition cap *g* is shown in Fig. 7 with a metal covering *h* having a ring *i* upon its outer end. The cap is formed with a socket *h'* at its open end to 50 closely fit the nozzle *b*, and with an internal thread *g'* to screw upon the thread *d*, as usual.

The extension-member consists of the tube *k* having a lining *l* which is slotted 55 from one end at *m* for the greater part of

its length, to fit upon the stud *f*. Such lining is fitted to slide smoothly upon the shell *e* with the stud in the slot *m*, the stud thus limiting the outward movement of the extension tube and preventing its rotation 60 upon the body.

To retain the lining securely in the shell, the extension-tube has a shoulder *k'* at its inner end fitted to one end of the lining, and at the opposite end the tube is closed 65 by a plug *n* which is made of suitable size to fit the open socket *h'* of the cap. The plug is not inserted in the outer end of the tube until the latter with its lining is slipped upon the shell *e* from the direction 70 of the pen *c*. The plug *n* has a collar *n'* fitted to the bore of the tube, and when the tube is thus slipped upon the body, as shown in Fig. 3, the collar is inserted in the tube and locked therein by turning a flange *o* 75 upon the end of the tube. The collar may also be secured to the tube by solder, if desired. The construction thus provides for the convenient assembling of the parts and the securing of them together so as to retain 80 them permanently in working condition.

The tube *k* serves as a cover to support and strengthen the slotted lining *l* which fits tightly therein, and is held therein by the 85 flange *k'* and the collar upon the plug *n*. The plug prevents the extension-tube from sliding too far upon the shell or body of the pen.

This invention furnishes a convenient and 90 effective means of converting an ordinary fountain pen into an extension pen, and thus produces an article short enough to carry in the pocket, while at the same time constructed for extension to a convenient length for 95 use in writing.

Having thus set forth the nature of the invention what is claimed herein is:

1. An extension fountain pen having a hardened composition body, a metallic shell 100 pressed tightly upon the body and having a lateral stud at its outer end, an extension tube provided with flange *k'* at its inner end adapted to slide upon the shell, a lining fitted within the extension tube and adapted 105 to slide upon the other and having one end in contact with the flange *k'* and having a slot to engage the lateral stud, and the outer end of the extension tube having a plug secured in the tube to retain the lining therein. 110

2. An extension fountain pen having a hardened composition body, a metallic shell pressed tightly upon the body and having a lateral stud at its outer end, an extension tube provided with flange k' at its inner end adapted to slide upon the shell, a lining fitted within the extension tube and adapted to slide upon the shell and having one end in contact with the flange k' and a slot to

engage the lateral stud, and the outer end 10 of the extension tube having a flanged plug with a collar fitted inside the extension tube and a flange turned over such collar upon the end of such tube, the collar serving to retain the lining within the extension tube. 15

In testimony whereof I have hereunto set my hand.

HARRY P. FAIRCHILD.
